CLAIM

The ornamental design for an aerosol sprayer actuator, as shown and described.

DESCRIPTION

FIG. 1 is a top front perspective view of an aerosol sprayer actuator, showing my new design;

FIG. 2 is a left side elevational view thereof, the right side being a mirror image thereof;

FIG. 3 is a bottom plan view thereof;

FIG. 4 is a front elevational view thereof; and

FIG. 5 is a rear elevational view thereof.

FIG. 1

FIG. 5

FIG. 2

FIG. 3

FIG. 4
